Attorney

UNITED STATES PATENT OFFICE.

FRED A. HOMEWOOD, OF GLENDO, WYOMING.

SPARK-PLUG.

1,397,634.

Specification of Letters Patent.

Patented Nov. 22, 1921.

Application filed March 12, 1921. Serial No. 451,759.

To all whom it may concern:

Be it known that I, FRED A. HOMEWOOD, a citizen of the United States, residing at Glendo, in the county of Platte and State 5 of Wyoming, have invented certain new and useful Improvements in Spark-Plugs, of which the following is a specification, reference being had to the accompanying drawings.

10 This invention relates to certain improvements in spark plugs, and it is primarily an object of the invention to provide a novel and improved device of this general character which is an improvement on the form 15 of spark plug embodied in my prior pending application, Serial No. 355,348, filed January 31, 1920.

Another object of the invention is to provide a spark plug embodying novel and improved means whereby the primary electrode is effectively cooled in a manner to prevent the firing end or point of such electrode becoming unduly heated or hot enough to scale and whereby the gapping or arcing of 25 the spark is materially facilitated.

It is also an object of the invention to provide a spark plug with novel and improved means whereby a materially large and intense spark is produced and wherein the gapping or arcing is from the primary electrode to the body or shell proper.

An additional object of the invention is to provide a novel and improved spark plug wherein the primary electrode or conductor is hollow and provided with means whereby a down and up draft may be had therethrough.

The invention consists in the details of construction and in the combination and arrangements of the several parts of my improved spark plug whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the 50 better understood, I will now proceed to de-

scribe the same with reference to the accompanying drawings, wherein:

Figure 1 is a vertical sectional view taken through a spark plug constructed in accordance with an embodiment of my invention;

Fig. 2 is a view in bottom plan of the device as illustrated in Fig. 1; and

Fig. 3 is a sectional view taken substantially on the line 3—3 of Fig. 1.

As disclosed in the accompanying drawings, B denotes the body or shell of a spark plug and which body or shell is of a conventional type. Held in the body or shell B by the nut N is the insulating core C. Disposed through the core C at substantially the axial center thereof is the primary electrode or conductor E.

The periphery of the reduced or connecting end portion of the body or shell B is 70 provided with the external threads 1 but said threads terminate a distance inwardly of the lower or outer end of said portion of the body or shell B. The end portion of the body or shell B outwardly of the threads 75 1 has pressed therefrom or otherwise formed an inwardly directed and relatively large protuberance 2, preferably parti-spherical in form. The protuberance 2 constitutes the secondary electrode and said protuberance 80 coacts with the firing end portion of the primary electrode in a manner to assure a relatively large and intense spark. This construction is preferred because the body or shell B through the secondary contact as afforded by the protuberance 2, permits the requisite travel of the electrical energy with 85 a minimum of resistance.

The primary electrode or conductor E is hollow or tubular and has its firing end 90 closed. Extending longitudinally of the bore 4 of the electrode E is a partition 5 extending from a point in close proximity to the closed or firing end 3 of the electrode to the opposite or outer end of such electrode. 95 The partition 5 divides the bore 4 of the electrode E into the chambers or compartments a and b and the lower end portions of said compartments are in communication one with the other at the firing extremity of the 100

electrode through the port 6 which is provided by the space between the inner end of the partition 5 and the closed 3 of the electrode E.

- 5 The outer end of one of the chambers or compartments, as *a*, is closed by the head 7 while the outer end of the second compartment or chamber, as *b*, is open. Threaded upon the outer end of the electrode E is a 10 nut 8 which coacts with the adjacent end of the core C to maintain the electrode in applied position, the opposite end portion of said electrode being provided with an enlargement 9 coacting with the adjacent or 15 firing end of the core C. The outer end portion of the bore of the nut 8 is enlarged to afford a chamber 10 and disposed through the wall of said chamber are the ports 11, preferably three in number, and which provide 20 means whereby air may have ready ingress within the chamber 10.

The portion of the electrode E within the chamber 10 is provided in its wall with a port 12 which affords communication between 25 the chamber 10 and the chamber or compartment *a*. Also threaded upon the outer end of the electrode E is a second nut 14, the inner end portion of said nut 14 being enlarged, as at 15, whereby said nut 30 14, when applied, closes the outer or open face of the chamber 10 of the nut 8. The outer portion of the bore of the nut 14 is reduced to provide an eduction vent or port 16, said port or vent 16 being in communication with the upper open end of the compartment or chamber *b* of the electrode E.

As the eduction port or vent 16 is a material distance above the port 12, an effective up and down draft is effected through the 40 electrode E, the heated air passing upwardly of the chamber *b* and out through the eduction vent or port 16 while the cool air is drawn through the ports 11 into the chamber 10 and from the chamber 10 through the port 45 12 into and downwardly of the chamber or compartment *a*.

The nuts 8 and 14 may serve as binding elements to hold a suitable conductor in electrical connection with the electrode E and 50 particularly when said conductor is provided with a flat terminal as now often used. In the event such conductor is provided with a snap terminal, the same may be engaged with the outer or extended portion of the 55 nut 14.

From the foregoing description it is thought to be obvious that a spark plug constructed in accordance with my invention is particularly well adapted for use by reason 60 of the convenience and facility with which it may be assembled and operated, and it will also be obvious that my invention is susceptible of some change and modification without departing from the principles and spirit 65 thereof and for this reason I do not wish to

be understood as limiting myself to the precise arrangement and formation of the several parts herein shown in carrying out my invention in practice except as hereinafter claimed.

70

I claim:

1. A spark plug including a hollow electrode having its firing end closed, and a partition extending within the bore of the electrode and terminating at a point spaced 75 from the closed end of the electrode, said partition dividing the bore into two compartments, the outer end of one of the compartments being closed and the adjacent end of the second compartment being open, the 80 wall of the first compartment being provided with a port in communication with the atmosphere.

2. A spark plug including a hollow electrode having its firing end closed, a partition 85 extending within the bore of the electrode and terminating at a point spaced from the closed end of the electrode, said partition dividing the bore into two compartments, the outer end of one of the compartments 90 being closed, the wall of said last named compartment being provided with an induction opening, and a member surrounding the electrode and provided with a chamber with which the port of the electrode communicates, the wall of the chamber being provided with a port in communication with the atmosphere.

3. A spark plug including a hollow electrode having its firing end closed, a partition 100 extending within the bore of the electrode and terminating at a point spaced from the closed end of the electrode, said partition dividing the bore into two compartments, the outer end of one of the compartments being closed, the wall of said last named compartment being provided with an induction opening, a member surrounding the electrode and provided with a chamber with which the port of the electrode communicates, the wall of the chamber being provided with a port in communication with the atmosphere, a face of the chamber of the member being open, and a nut engaged with the electrode and closing the open face of 105 the chamber of the member, the second chamber of the electrode being in communication with the bore of the nut.

4. A spark plug including a hollow electrode having its firing end closed, a partition 110 extending within the bore of the electrode and terminating at a point spaced from the closed end of the electrode, said partition dividing the bore into two compartments, the outer end of one of the compartments being closed, the wall of said 115 last named compartment being provided with an induction opening, a member surrounding the electrode and provided with a chamber with which the port of the electrode com- 120

125

130

municates, the wall of the chamber being provided with a port in communication with the atmosphere, a face of the chamber of the member being open, and a nut engaged with 5 the electrode and closing the open face of the chamber of the member, the second chamber of the electrode being in commun-

cation with the bore of the nut, said bore of the nut communicating with the atmosphere at a point outwardly of the adjacent end of 10 the electrode.

In testimony whereof I hereunto affix my signature.

FRED A. HOMEWOOD.
